UNITED STATES PATENT OFFICE.

ORVILLE M. KNOX, OF ONEIDA, NEW YORK.

DIGGING AND TAMPING IMPLEMENT.

SPECIFICATION forming part of Letters Patent No. 618,469, dated January 31, 1899.

Application filed June 12, 1896. Serial No. 595,249. (No model.)

To all whom it may concern:

Be it known that I, ORVILLE M. KNOX, of Oneida, in the county of Madison, in the State of New York, have invented new and useful 5 Improvements in Digging and Tamping Implements, of which the following, taken in connection with the accompanying drawings, is a full, clear, and exact description.

This invention consists in a novel construction of a digging implement combined with a tamping-tool by means of an intervening metal tube which serves as a handle for the two tools, the whole constituting an improved article of manufacture which is simple and inexpensive and at the same time light, convenient, and efficient in operation, especially in setting fence-posts, and possesses superior strength to resist the strain it may be subjected to in its operation.

20 The invention is fully illustrated in the annexed drawings, in which—

Figure 1 is a front view of my invention. Fig. 2 is a longitudinal section of the handle portion, showing the attachment of the digging and tamping tools; and Figs. 3 and 4 are respectively detached side views of said tools.

Similar letters of reference indicate corresponding parts.

25 *b* represents the digging-tool, *c* the tamping bar or tool, and *t* the handle, to opposite ends of which the aforesaid two tools are attached. Said handle consists of a straight metal tube, such as a section of gas-pipe or other suitable stiff tubing.

30 The digging-tool consists of a straight steel blade which has one end formed with an attaching-stub *a* in its center and in line with the blade and the opposite end formed with a cutting edge *a'*, which is at right angles to the axis of said stub. This stub is of cylindrical shape and of the same diameter as the interior of the metal tube *t*, into which it is inserted and either welded or brazed. The blade *b* is of the shape of a spud, which is 35 straight throughout and in line with the axial center of the handle *t*, as shown in Fig. 3 of the drawings. Said blade is thus capable of

resisting severe strains applied endwise thereto in the operation of digging or cutting up hard material—such as hard-pan, gravel, and 50 even capable of cutting through stone—and by its aforesaid position in relation to the axis of the handle the said spud is caused to cut diametrically across the hole in the process of being dug, and by turning the handle 55 part way between the successive cuttings the bottom of the hole is cut up more effectually and completely across the entire width of the hole.

The tamping-tool *c* consists of a steel plate 60 or bar which is beveled toward one of the longitudinal edges of the plate to form a blunt tamping edge *c* and is formed with the attaching-stub *c'* in the center of the opposite edge, which stub is cylindrical and is either 65 welded or brazed in the end of the metal tube *t* opposite to that to which the digging-tool is attached. The said tamping-tool is made solid and is thereby enabled to better withstand the severe usage to which it is subject- 70 ed than if made hollow or with an opening therein.

The tube *t* forms a light and very stiff handle for the two tools *b* and *c*, which are readily brought interchangeably into use by merely 75 reversing the said handle end for end.

What I claim as my invention is—

In a digging and tamping implement, the combination with the open-ended tube, the blade formed straight throughout and a stub 80 in the center of one end and in line with the blade and said stub fitting in and secured to one end of said tube, of the solid tamping-bar provided with a stub fitting in the opposite end of said tube and said bar being beveled from the inner to the outer sides and the ends projecting beyond the stub thereof, substantially as described.

In testimony whereof I have hereunto signed my name this 30th day of May, 1896. 90

ORVILLE M. KNOX. [L. S.]
